UNITED STATES PATENT OFFICE

LEVITT LUZERN CUSTER, OF DAYTON, OHIO

AMUSEMENT APPARATUS

Application filed April 4, 1929. Serial No. 352,579.

My invention relates to an amusement apparatus.

It is an object of my invention to provide an amusement apparatus in which the passenger will be moved in a circular or other path in a chair, but the exact position of the chair will be controlled by the position of the amusement apparatus, the effect of gravity and centrifugal force on the chair and the relative position of the chair with respect to the rest of the apparatus.

It is an object to provide in such an apparatus a chair the position of which can apparently be controlled by an operator of the chair, but which in reality will be impossible as the movement of the chair will be so erratic that the ordinary user will have no possibility of controlling the unexpected movements of the chair.

20 It is a further object of my invention to provide for a tilting of the entire amusement apparatus at unexpected intervals from points outside of the apparatus so as to produce varying effects by gravity and centrifugal force upon the chairs.

A further object is to provide such a tilting means that there is no possibility of the passengers being injured, particularly with respect to the loading and unloading platform.

30 Referring to the drawings:

Fig. 1 is a top plan view of the entire apparatus having a portion of the loading platform broken away to show the pivot arrangement of the elevating subframe;

35 Fig. 2 is a section on the line 2—2 of Fig. 1;

Fig. 3 is a similar view showing the apparatus in elevated position;

Fig. 4 is a detail section through the chair mounting;

40 Fig. 5 is a side elevation of the chair and its mounting on the revolving platform.

Referring to the drawings in detail, 1 is a loading platform upon which the passenger steps prior to entering the chairs 2. The 45 chairs 2 are pivotally mounted upon the pivot pins 3, on the revolving amusement frame which comprises a plurality of outwardly extending members 4 from a central platform 5. These members 4 are joined together 50 by web pieces 6. This provides a wheel-like

structure of which the members 4 are spokes, the member 6 a rim and the platform 5 a hub. This amusement platform has a driving axle 7 driven by a motor 8 from a suitable source of power. The platform itself 55 has a plurality of wheels 9, which travel on a circular track 10 that is mounted upon an annular track supporting frame 11. The cross frame members 12 are mounted upon the frame members 13 constituting a sub-frame the end of which is connected together 60 by the cross frame member 14. At this end the pivots 15 mounted on the frame 16 provide the pivotal supports for rocking the frame. A supplementary platform member 17 is mounted on the cross frame members 12 to form a bearing support for the bearing 18 in which the axle 7 fits.

This axle 7 has its lower end formed into 70 a bearing 19 which receives the upper end of the piston rod 20, thus forming a universal joint between the amusement apparatus and the piston rod 20. This piston rod 20 is connected to a piston 21 which works within the pivoted cylinder 22 that is pivotally mounted 75 on the support 23 within a pit 24. Air is supplied through the port 25 beneath the piston 21 within the cylinder 22. Such air may be admitted at intervals and allowed to pass back through the port 25, thus controlling the 80 rising and falling of the entire amusement apparatus. The wheel support consisting of the hub 5, spokes 4 and rim 6, with the seats 2 mounted on the pivot supports 3 at the end of each spoke rotates under the influence 85 of the motor 8 while the frame 13 swings about the pivots 15 causing the rising and falling of the subframe 13.

Turning to the mounting of the seats, particularly as shown in Figs. 4 and 5, it will be 90 observed that the pivot studs 3 carry loosely a swinging arm 26 to the free end of which is attached a vertically extending pivot pin 27. On this pin is permanently attached a large sprocket 28. On the upper end of the pin is freely swiveled the chair 2 by means of bearing 29. The chair is held in position by the pin 30 and washers 31.

Mounted in the floor 32 of the chair 2 is a 100 steering column 33 on the top of which is a

steering wheel 34 and on the bottom of which is fixed a small sprocket 35. On the sprockets 35 and 28 there is mounted a chain 36.

The operation of the hand wheel 34 results in the movement of the chair about the pivot pins 27. The centrifugal force of the amusement wheel as it rotates on the chair of the periphery will tend to draw the chairs outwardly, but the weight of the passengers within the seat 2 will vary with respect to the pivot shafts 3 and 27, depending upon the movements of the steering wheel 34. The third force comes into play when the platform is unexpectedly tilted so that the chair will tend to move under the influence of gravity. Thus I have provided an amusement apparatus in which unexpected movements of the chair will take place which the ordinary user will seek to control but can not do successfully, because his very efforts to control change the pivotal positions of his chair and thereby set up erratic movements that are influenced by centrifugal force, by the position of his weight and by gravity due to tilting unexpectedly of the entire apparatus.

It will be understood that I desire to comprehend within the scope of my claims such modifications as may be necessary to adapt my invention to varying conditions of use and to varying purposes.

Having thus fully described my invention, what I claim is new and desire to secure by Letters Patent, is:

- 25 1. In combination, a revolving platform, means to revolve the platform, a plurality of passenger chairs on the periphery thereof, freely mounted arms on said platform pivotally supporting said chairs, means for freely mounting said chairs on the end of said arms, means controlled by the occupants of said chairs for moving said chairs about said last mentioned pivotal support whereby the position of the weight of occupants will be caused to vary with respect to the first mentioned pivotal support of the chairs.
- 30 2. In combination, a subframe, a frame for pivotally supporting said subframe at one end, a cylinder piston and piston rod universally connected to said subframe, a revolving platform mounted on said subframe, means to rotate said platform on the subframe, chairs on said platform on the margin thereof and a loading platform surrounding said revolving platform whereby said subframe, chair and revolving platform may be tilted without danger to the occupant of the chair being caught between the loading platform and the revolving platform.
- 35 3. In testimony whereof, I affix my signature.
LEVITT LUZERN CUSTER.
